SEPARATOR FOR LIQUIDS HAVING DIFFERENT SPECIFIC GRAVITIES

Herbert Alexander Thompson, Benton,
Northumberland, EnglandApplication February 24, 1932, Serial No.
594,959½. In Great Britain January
25, 1932

16 Claims. (Cl. 210—43)

This invention relates to separating devices or the like for separating liquids of different specific gravities from a mixture of such liquids, the separator being of the type which consists of a casing having arranged in its interior a number of quiescence chambers through which the liquid mixture is caused to flow for the purpose of enabling the difference in the specific gravity of the liquids forming the mixture to become effective in separating the liquids, the rate of flow of the liquid mixture through the apparatus being made as low as possible for this purpose.

Separators of this type have been employed for removing any oil leakage from the condensed water drawn from the steam heaters of oil-burning installations to enable such condensate to be so cleansed that it may be returned to the steam boilers direct for feed-water. In the type of construction above referred to the divisions between the chambers are usually so arranged that the flow of mixture to be separated into its component liquids is made to take an up and down or other tortuous course.

In order to allow the separation to be as complete as possible it is usual to arrange that the liquid mixture has a considerable distance to travel within the confines of the apparatus and for this reason the liquid mixture leaving one quiescence chamber, where some of the component liquids separate out, is usually brought into the next quiescence chamber at the bottom thereof so that the lighter component of the mixture has to rise through the whole of the chamber. Besides the risk of contaminating the heavier component of the mixture which may have separated out at the bottom of the second quiescence chamber the whole of the liquid in this chamber is agitated by the entry of the mixture at the bottom thereof and the necessary degree of stillness is not obtained. These disadvantages are overcome, in the construction according to the present invention by arranging that the entry of the mixture into any quiescence chamber occurs as near as possible to the point where one of the separated liquids is collected and also at a level at which the horizontal cross-sectional area of liquid is greatest so that the entering liquid is enabled to distribute itself over the largest possible surface and thereby attain maximum quiescence as soon as possible.

In order to determine the most efficient and compact form for such apparatus, I have carried out a number of experiments with a known type of apparatus of my own design which is used for removing oil from condensed water from the

steam heaters of oil burning installations as above referred to. This apparatus usually consisted of a rectangular tank having arranged internally thereof a series of divisions or baffles so arranged that the condensate flowed for example, over the top of the first baffle, under the second, over the top of the third baffle and so on so that by this means the oil, being of lighter specific gravity than the water, tended to float to the surface of each chamber formed by the baffles from which it was collected. By using a suitable number of divisions the whole of the oil was more or less removed by this means, but to secure complete removal of the oil I usually arranged that the last chamber before the outlet was provided with a perforated plate bottom and loose lid between which was placed a filter bed of broken coke, rubble, sponge or filter cloths which effectively removes the last traces of oil.

The main objection to the use of such apparatus is that for a given output the separator tends to become very unwieldy in length owing to the number of chambers employed to obtain high efficiency and, as the result of my experiments to determine the best method of providing a smaller and more compact apparatus, I found that it was advantageous to have at the inlet a swirl chamber or compacting chamber in which the mixture of liquids to be separated, such as, for example, oil and water, was given a swirling action and by the turbulence caused the particles of oil coalesced into large masses which more readily flowed to the top of the chamber than did tiny globules merely discharged directly into a quiescence chamber.

Having united the globules of oil into larger masses I then found that it was advantageous to effect the removal of these large masses as quickly as possible from the main flow and I therefore arranged a collecting chamber or oil dome adjacent to the line of flow from the swirl chamber but off the direct line of flow of the mixture, so that once these masses of oil entered the dome they were in a chamber which was free from any disturbances caused by the main flow currents. Thus in the case of a mixture of oil and water in which the oil is of low specific gravity the oil dome would be arranged above the main flow.

In carrying out the experiments I ascertained that certain particles of oil sometimes behaved in an erratic manner and tended to follow the main flow, and on observing these particles I found that they were really globules of water enclosed in an envelope of oil and to remove these from the main flow I arranged that the mixture

stream should enter a first stage quiescence chamber of relatively large capacity in relation to the flow volume to enable these particles, which were almost of the same specific gravity as that of the mixture, to assert their rising power which would carry them towards the oil dome before they could be swept into the next quiescence chamber by the flow current. Furthermore, I found that whenever these oil globules touched an oily surface they tended to adhere thereto and in view of this feature and to assist the globules in rising I designed the cross-section of the quiescence chambers in such a manner that the side walls thereof were inclined inwardly and upwardly towards the top surface and the oil dome. Also, as the main flow of liquid mixture was at the level of the inlet I observed that the horizontal cross-sectional area of water should be greatest at that level to obtain the highest degree of quiescence. For these reasons, namely, to direct the separated oil towards the oil dome and to provide the highest degree of quiescence at the inlet level I prefer to make the quiescence chambers of ovate cross-section as this form of construction gives sufficient depth of liquid without having an equal volume of liquid at the top to that at the bottom as the oil content is always at its lowest percentage at the bottom of the chamber. The swirl chamber is also preferably made of ovate cross-section as it enables curved vanes and the like for obtaining turbulence to be dispensed with, for by directing the flow downwards at its entry into the swirl chamber the stream is caused to break up into two ascending currents which are turned inwards at the top by the curved walls and so start a gyratory movement within the chamber, the velocity of this movement being sufficient to impact the smaller particles of oil into larger masses as desired. The provision of these three features, namely, the swirl chamber, an ovate cross-section of quiescence chamber and the provision of an oil dome off the line of flow of liquid, enables the rate of flow through the apparatus to be increased as compared with apparatus of the previously known type of an equal size and capacity.

By carrying out further tests for increasing the rate of flow, I found that whilst in the first stages the main masses of oil were effectively removed there was now present at the higher rates of flow the danger of oil enveloped particles being discharged through the outlet into the next quiescence chamber, but, instead of increasing the length of the apparatus by adding further quiescence chambers to the outlet end, I find that the ovate section adopted in the case of the initial quiescence chamber enables the additional quiescence chambers to be arranged on a return flow principle by enclosing the first chamber in a second or outer chamber also of ovate shape.

The apparatus hereinafter described in detail for the separation of oil and water is therefore constructed in the manner indicated above, namely, with a first-stage or inner quiescence chamber of ovate cross-section surrounded by an outer casing or shell, also of ovate cross-section and forming further quiescence chambers, the whole being surmounted by an oil dome from which the separated oil is drawn off. The mixture to be separated is led first into a swirl chamber at the inlet end of the apparatus and is then passed through successive quiescence chambers from which the oil rises to the oil dome while the separated water is drawn off from the last quiescence chamber.

By arranging the quiescence chambers one inside the other the inner shell and interior parts, being exposed to the same pressure on each side as they are merely immersed in the liquid mixture, can be made of the lightest possible structure consistent with practical manufacture and a considerable saving in the cost of manufacture can be effected as only the outer shell and main oil-dome need be made strong enough to stand the working-pressure.

At the bottom of the inner or first-stage quiescence chamber and at a point farthest from the inlet, I arrange an outlet passage communicating with the space enclosed between the outer and inner shells and forming the second and later stages of quiescence chambers, and in addition I also place a flow-direction plate below this outlet opening, to impart an upward motion to the flow in the second chamber.

This direction plate directs the flow to the widest area of the outer chamber and the narrowing spaces between the upper portions of the two shells form oil collection spaces or pockets which are also clear of the main currents and by which the oil is directed towards the oil dome. These oil-spaces are connected internally to the oil-dome of the apparatus by so forming the top side of the inner shell adjacent to the main oil-dome, that it forms communicating passages for this purpose. Instead of connecting the oil-collection pockets with the oil dome in this manner they may be connected thereto by internal or external pipes.

By adding stepped flow plates and divisions in the outer chamber a further series of quiescence-chambers within the length of the apparatus are obtained.

As the spaces within the main oil-dome, the inner and outer chambers are all in communication they are in static balance as regards the water-flow pressure, and any oil separated in the outer or later-stage quiescence chambers can flow freely up to the main oil-dome by reason of its lower specific gravity compared with that of the main-flow water.

The main flow of mixture to be separated can pass freely whilst oil is collecting in the oil-dome, and the latter may be emptied when full by opening a suitable discharge valve to enable the oil to be led away by a pipe to a collection tank or other suitable place. The oil discharge valve may be operated by hand, or the oil can be drawn off automatically as soon as a predetermined quantity of oil has collected in the oil dome by means of a standard float mechanism operating the valve directly to open or close the latter when the oil reaches a predetermined high or low level in the dome, the float being suitably balanced so that it will sink in oil but float in water or the heavier of the two liquids being dealt with.

As the mechanical effort due to the flotation difference between the specific gravities of the liquids dealt with is often very small, however, I prefer to use such a balanced float only as an indirect control for opening and closing the oil valve.

For this purpose I arrange a suitable balanced float within the oil-dome, connected by levers to a shaft, housed in suitable bearings, one end of the shaft passing out through the wall of the dome to the exterior, being kept water-tight by a gland and stuffing box. To the outer end of this shaft is rigidly fixed another lever to which is attached a movable balance weight for adjusting purposes. As the float rises or falls within the

5 dome, so the external lever moves correspondingly outside and this lever is employed to operate an easily moved piston-valve controlling the main piston-valve or slide-valve of a cylinder and piston, the piston rod of the latter being suitably connected to the spindle of the oil-discharge valve.

10 The spindle of the first mentioned piston-valve has adjustable triggers attached to it at a suitable distance apart, so that the external float-operated lever is allowed lost motion between these triggers and the valve spindle is only moved towards the end of either the up or down stroke of the lever when it engages one or the other of the triggers.

15 This arrangement enables the discharge valve to remain closed whilst the dome is filling with oil to a predetermined level, and, although the float will sink as the oil content increases, the piston valve will not be operated until the external lever reaches the valve trigger near the end of its upward stroke and carries it to the limit of its stroke thereby causing the main engine slide valve to be thrown over and so admit fluid 20 under pressure to one side of the piston which moves in the cylinder and opens the oil valve.

25 The oil-discharge valve will then remain open until the oil has been discharged from the dome to a given level and, as the oil is discharged, water will rise in the dome to take the place of the discharged oil, causing the float to rise and the external arm to fall and when the arm meets the lower piston-valve trigger near the end of its stroke it will carry it downwards with it and so reverse the engine slide valve, whereon 30 fluid under pressure will be admitted to the opposite side of the piston so that the latter moves to close the oil valve. During these operations the opposite side of the piston to that on which pressure is applied is of course open to exhaust.

35 Instead of using pressure alternately on each side of the piston for opening and closing the oil-discharge valve, the latter may be maintained closed by a loaded spring attachment and opened against the action of the spring by means of the mechanism just described but in which fluid under pressure is admitted to one side of the piston only, the valve being closed by the spring when the pressure is released. With this arrangement the opposite side of the piston to that on which pressure is applied is continually open to exhaust but the working side is alternately open to pressure or exhaust depending on position 40 of the external lever which operates the cylinder slide-valve.

45 If the separator is working under pressure other than atmospheric pressure, a pipe may be led from, say, the lower chamber to the operating cylinder and the water or other fluid utilized to operate the piston, but if desired steam, air or other fluid under pressure from an external source may be employed for this purpose.

50 Alternatively the external lever may be used in any suitable manner to control electrical switch-gear of any of the well-known trip-gear types or it may be employed to throw over alternately from one side to the other the well known type of mercury-tube contact switch which may control directly, or through relay-switches, suitable electrically operated mechanism for opening the oil-discharge valve, or suitable electrical alarms, signal-lamps, sirens or whistles or the like may be operated in this manner or directly by the external float-arm, particularly in cases 55 where the control of the oil-valve is by hand.

To assist the separation of the oil and render it more fluid, I may arrange steam heating-pipes or electrical heating-elements in any suitable position or positions within any of the chambers, preferably along the crown of the top inner chamber and around the internal circumference of the oil-dome clear of the float gear, if this is fitted. With very viscous oils the heating of the dome contents would prevent sticky masses of oil clinging to the float mechanism and upsetting the adjusted balance of the gear.

5 The filtering chambers filled with coke, sponges, filter-cloths and the like may be fitted in cases where the apparatus is used in processes where not the slightest trace of the oil or other contaminating fluid must be allowed to pass out of the separator, or, if desired, the apparatus may be connected at its outlet to ordinary standard filters sold for this purpose.

10 Since oils are now in use which are heavier than water the apparatus is so arranged that it can be used in an inverted position, the oil-dome then becoming an oil-well or sump for this heavier type of oil, the separated oil being discharged in a similar manner to that previously described.

15 On this account the apparatus may be used in pairs, one device being inverted to remove heavy oil from the mixture while the other removes a second oil of a lighter nature so that an oil-free discharge is thus obtained.

20 Furthermore, by the use of an inverted apparatus it is possible to deal with, for example, petrol contaminated with water, a small form of the apparatus being inserted in the petrol-supply pipe leading to the carburettor of a petrol-engine, with the result that water, or even solid matter, is precipitated into the inverted dome, which may be in the form of a glass cylinder 25 suitably held in place by a removable cover which is provided with a drain-cock or valve to draw off the separated liquid. In this case, instead of the hand-operated cock, a needle-valve may be arranged to be opened directly by a suitable balanced float, which will sink in petrol but float in water. As apparatus for use in this manner 30 may have to be produced at the lowest possible cost, it may be constructed without the removable glass sump and the whole apparatus may be manufactured from pressings or stampings, welded, brazed or soldered together, so that a 35 sealed vessel is formed without removable covers or joints for access to the interior.

40 Instead of constructing the chambers of ovate cross-section, any other suitable form may be employed, such as circular, rectangular, triangular and the like, as although these are not so efficient, they will yet form an apparatus constructed on the lines previously described.

45 Constructional forms of apparatus according to the invention are illustrated in the accompanying drawings, wherein:—

50 Fig. 1 shews a sectional view in side elevation of the apparatus, shewing the oil-dome, swirl-chamber, and the various quiescence chambers and internal parts.

55 Fig. 2 is a part-sectional plan view of this device with the oil dome cover removed, the section being taken on line 2—2 of Fig. 1.

60 Fig. 3 is an external end view of Fig. 1 showing the arrangement of inlet and outlet pipes and valves.

65 Fig. 4 is a part sectional end elevation of Fig. 1.

70 Fig. 5 is a sectional side view of a modified arrangement of device.

75 Fig. 6 is a part-sectional end view of Fig. 5.

Figs. 7 and 8 are detail views of the oil-discharge valve operating gear, showing modifications.

And Figs. 9, 10, 11 and 12 are sectional and outside end elevations, a part-sectional side elevation, and an underside plan, respectively, of an inverted separator arrangement suitable for insertion in the petrol supply pipe of petrol engines.

Referring first to Figs. 1 to 4 the apparatus consists of a main or outer shell 1 of ovate cross-section inside which is arranged an inner shell 2, also of ovate cross-section, and which extends from end to end of the outer shell 1. An oil dome 3 is secured on the top of the outer shell 1, preferably in a mid-position as shewn. The oil-dome 3 is fitted with a removable cover 4 having an oil-discharge branch 5 to which a suitable oil discharge valve 6 is fitted, this valve being arranged to be operated by hand or automatically by means such as the mechanism to be later described. The shell 1 is provided with end plates or covers 7, 7¹ which may be fixed or removable as desired and the end plate 7¹ is provided with an inlet opening 8, situated within the confines of the inner shell 2, and an outlet opening 9 is provided leading from the space below the inner shell 2. Over the inlet opening 8 is fixed a flare-mouthed direction plate 10 by which the flow of entering liquid is directed downwardly into the converging space of a swirl-chamber 11 formed at the inlet end of shell 2 by arranging a suitable division plate 12 across the width of shell 2. The top edge of this plate 12 is provided with a lip 13 to act as a flow-direction plate or guide.

The quiescence chamber 14 formed by the remainder of the inner shell 2 is in communication with the lower space by means of a passage 15 in the bottom of shell 2, such passage being preferably formed by shell 2 being bent into flanges 16 at this point. A vertical or inclined flow-directing plate 17 is fitted to inner shell 2 at a suitable position as shewn adjacent the passages 15 and below these passages is fitted a curved baffle plate 18 which is supported, and connected to shell 2, by plates 19.

A suitable number of division plates 20 are arranged as shown in the space between the outer and inner shells 1 and 2 to divide this space into a number of additional quiescence chambers 21, the plates 20 also acting as supports or stiffeners for the inner shell 2. These plates 20 are not carried right to the top of the space between the two shells in order that each chamber 21 may be in communication with its neighbour by reason of the gaps or passages 22 so formed. The spaces bounded by the outer and inner shells 1 and 2, and the plates 20, or these plates and the end plates 7, 7¹, form upwardly directed passages 21a.

Flow-directing plates 23 arranged alternately with plates 20 are fitted at the bottom of the outer shell 1 to act as diverting plates to give the main flow an upward motion and these also act as stiffeners or ties for the shell 1.

In Figs. 1 and 4 the inner shell 2 is shewn secured along its top side to the outer shell 1 for its full length except where the oil dome 3 is fitted to the outer shell. At this point the sides of shell 2 are carried upwards into dome 3 by means of flanges 24 or the like, so that a passage or space 25 is formed on each side between the flanges 24 and the walls of dome 3 and these passages 25 thus form continuations of the passages 22 previously referred to and so put the latter in

communication with the interior of dome 3. The flanges 24, by being carried into the dome, prevent eddy disturbances from the main flow in shell 2 interfering with the quiet rising of the separated oil from passages 22 into oil-dome 3.

Fig. 3 shows in dotted outline a suitable arrangement of connecting pipes and valves for connecting the apparatus into the main flow pipe system 26. Into the main pipe line 26 is inserted a T-piece 27, a shut-off valve 28, and a second T-piece 29. The T-piece 27 is connected to inlet valve 30 which is joined by pipe 31 and bend 32 to the inlet 8 of separator, while, by means of a bend 33, a pipe 34 and an outlet valve 35, the flow is led from outlet 9 back to the main pipe line. The valve 28 is inserted in the pipe line 26 to enable the flow to pass straight through the pipe 26, when this valve is opened and the inlet and outlet valves 30 and 35 are closed, so as to shut the separator off for cleaning or repairs without stopping the main flow discharge in case of need. If necessary a relief valve (not shown) may be provided in the pipes leading to the apparatus or in the device itself to prevent dangerous rise of pressure in the apparatus when starting it in operation.

Neglecting for a moment the automatic operation of the oil-discharge valve 6, the operation of the apparatus in actual use will now be described and, although the apparatus is intended for use with any mixture of liquids of different specific gravities, it will be described for the sake of clarity, as dealing with water contaminated with oil-fuel or other light oil.

On first starting the apparatus, it is filled by suitable means to the top of the oil-dome 3 with a supply of clean water, to prevent all its interior surfaces becoming coated with oil deposits. After this the valves 30 and 35 are opened and the valve 28 closed, thereby permitting the oil contaminated flow to enter inlet 8 where it is diverted downward by director plate 10 to the bottom of swirl chamber 11 where it is broken up into two streams which flow outwards to the walls of shell 2 which enclose the chamber 11, the division into two streams being assisted, if desired, by deflector 36 placed at the bottom of swirl chamber 11. As the walls of shell 2 converge at the top they direct the two streams into a circular path which starts a gyroscopic movement at each side. The two streams meet at the centre of swirl chamber 11 with the result that the oil particles are pounded together and so compacted that they coalesce and form large masses, which readily remove themselves from the disturbed area, by rising to the surface of the swirl chamber 11 where they pass out through the opening 13a arranged between the top of lip 13 of the division plate 12 and the top of shell 2.

These main masses of oil are thrust upwards against the top surface of chamber 14 and advance along same until they reach the opening 24a between the two flanges 24, where they pass up into the oil-dome 3, and are so taken as soon as possible out of the path of the main flow, which now proceeds along the line of the top surface of shell 2 through the quiescence chamber 14. It will be evident that the primarily separated mixture is introduced by way of the passage 13a at the highest possible level in chamber 14, so as to have beneath it a mass of quiescent water. On this account any small particles which have remained uncoalesced, such as oil-enveloped water globules, are diffused forward along this top level at greatly reduced speed, as

the volume of space 14 is many times the equivalent of inlet 8. Oily particles will therefore continue to rise to the surface, where, by coming into contact with the converging sides of shell 2, 5 they will tend to adhere and in due course creep up the walls in united streams and so also arrive in oil-dome 3 by way of passage 24a. Towards the end of chamber 14 the flow passes over the baffle plate 17, which causes the flow stream to 10 ascend and so bring any submerged oil-particles to the top before the main flow passes down into the lower quiescence chambers. The main flow now passes through passages 15 and in its descent the flow stream is diverted in an upward 15 direction by baffle 18 on reaching the lower chamber, so that any oil particles which may have been carried along are projected onto the inwardly inclined surface of the underside of shell 2 and these particles, along with others which 20 continue to rise out of the flow, ascend into the passages 21a between the outer and inner shells 1 and 2. These passages or spaces 21a are out of the path of the flow stream and so allow any separated oil to flow upwards and pass by the 25 passages 22 and 25 into the oil dome. The whole of the chambers being in hydrostatic equilibrium, ensures the transference of oil from these lower spaces 21 and 21a to the oil dome 3 by reason of the difference in specific gravities of the 30 oil and water.

The flow stream continues on and now meets the first director baffle 23, which, being either vertical or inclined, again imparts an upward motion to the flow, which gives any remaining 35 particles of oil assistance to reach the second set of spaces or passages 21a, these being situated between the two division plates 20. This further body of trapped oil passes to the oil dome 3 in a similar manner to that last described. The 40 flow stream now meets the second director baffle 23 with a similar result and this process is repeated according to the number of baffles 23 and divisions 20 fitted.

The cleansed flow stream finally leaves the 45 apparatus by the outlet 9, and is led by bend 33 and pipe 34 back to the main pipe line 26 and so to its ultimate destination.

It will be evident that, as the main flow proceeds, the oil dome 3 will become full of oil, and to empty this a discharge valve 6 may be opened 50 by hand, the pressure within the apparatus causing the oil to flow out, when it may be taken by a pipe to a suitable destination. Suitable test-cocks or gauge-glasses (not shown) may be fitted to the oil-dome 3 to ascertain the high and low 55 levels and so enable the operator to tell when to open or close the valve 6.

If the oil dome 3 requires to be frequently 60 emptied, it is desirable to employ an automatic device to operate the valve 6 and one construction of device for this purpose is illustrated in Figs. 1 to 4. Within the oil dome 3 is arranged a float 37 of suitable design, preferably arranged as shown in Figs. 1, 2 and 4, where it is shewn connected to twin parallel arms or levers 38 and 38a, which maintain the float in a horizontal position at all levels, the levers being rigidly coupled to shafts 39 and 39a which are carried in sockets or bearings 40 of suitable design. One end of shaft 39 is extended through the wall of dome 3 to the exterior, leakage being prevented by suitable means, such as a gland and stuffing-box 41, and to the outer end of shaft 39 is rigidly attached a lever arm 42 to which is movably affixed 70 a balance weight 43. The float 37 is designed to

float in water and submerge in oil and the balance weight 43 enables exterior adjustments to be made if necessary.

As the flotation effort of the float may not be sufficient for the operation of large valves direct I prefer to employ the float to operate only a small piston-type control valve, such as is commonly used to govern the working movements of the slide-valves of engine cylinders. This piston type control valve, the operating cylinder and its slide valve are indicated generally by reference numerals 44 and 45 as these may be of any well known type and their construction does not form part of the present invention. The piston-rod 46, is, however, modified at its outer end by fitting 10 a spring-coupling and shock absorber consisting of a casing 47 which is provided with a cover nut 48 and contains a spiral spring 49 of suitable strength. The oil-discharge valve 6 may be of any standard make or design, but modified by 15 omitting the usual screw-thread on its valve-spindle and employing a plain spindle 50 which is free to slide up and down through the stuffing box and gland of the valve, and attached to the outer end of the valve spindle 50, or formed thereon, is a collar 51 which is arranged to fit within the casing 47 of the coupling so that the spring 49 keeps it firmly in place against the inner face of nut 48 when the latter is screwed on to the casing 47. The oil discharge valve 6 is thus ad- 20 justably coupled to the piston of the operating cylinder, the spring 49 allowing for any difference of travel between the piston of the operating gear and valve 6 when wear occurs in the valve seating. The slide rod 52 of the piston valve 30 44 is extended and fitted with adjustable operating triggers 53 and 54 at a suitable distance apart to enable them to be engaged by the lever 42 near the limits of its travel to throw over the piston valve 44. 35

The operation of this mechanism is as follows:—

As shewn in Fig. 1, the float is in its highest position, which means that oil-discharge from dome 3 has just ceased, through the valve 6 being 45 closed by the operating cylinder 45.

Separated oil will again begin to collect in dome 3 and as it accumulates it will displace the equivalent water content, and the float 37 will follow the water level down since it is not designed to 50 float in oil. Consequently the exterior lever 42 will rise until it reaches the trigger 54 and as the lever 42 continues to rise it will lift trigger 54 and spindle 52 and raise the piston valve which causes the main slide-valve of the cylinder 45 to be re- 55 versed so that pressure is admitted to the top side of the cylinder, whilst the lower side is opened to exhaust, with the result that the piston moving in this cylinder is moved downwards and opens valve 6 through the medium of piston rod 46 and the valve spindle 50. 60

The oil is now discharged through outlet 5 and the level of the water in dome 3 will again rise, carrying float 37 upwards so that lever 42 moves downwards until it meets the lower trigger 53 65 which is then pushed downwardly as the float continues to rise, with the result that the piston-valve reverses the slide valve again, pressure is admitted to the lower side of the piston in cylinder 45 while the top side thereof is opened to exhaust, so that the piston rises and so closes valve 6. This sequence of operations is then repeated each time a predetermined amount of oil has 70 collected in the oil dome 3.

The oil-discharge valve-opening mechanism 75

may be operated by fluid under pressure supplied from any suitable external source, but when the separator is working under pressure other than atmospheric the mechanism may be actuated by 5 the fluid in the separator itself by means of a pipe 35 extending from a cock 56, fitted say, near the bottom of outer shell 1.

A modified form of the apparatus shown in Figs. 1 to 4 is illustrated in Figs. 5 and 6. The 10 construction in this case is in general the same as that of Fig. 1, but instead of the outlet 9 being placed in the lower part of plate 7¹, special internal outlet flow passages 57, are arranged at each side, between shells 1 and 2, at the end adjacent 15 plate 7¹, these passages meeting as one continuous passage at the top of shell 1, in which is arranged the outlet 9, to which is connected a suitable adapter 58, here shewn as a tapering cone, by which the outlet is connected to the flow 20 outlet pipe 34, or if desired, the pipe 34 may be attached direct to outlet 9. This arrangement ensures that the apparatus, once filled, remains so, and prevents the oil level falling to the lower 25 spaces should the valve 35 have been left open when the apparatus has been stopped. The arrangement of overhead pipes in Fig. 3 also achieves this purpose, but in a more cumbersome manner.

In this construction, also, the top of shell 1 is 30 shown as being sloped up towards the oil dome 3, only the lower part of which is shown, in order to assist the oil in its upward passage to the oil dome and inner shell 2 also follows this same slope where it is attached to shell 1. Filter beds 35 59 and 60 are also shown as fitted at the flow outlet end of chamber 14 and between the two quiescence chambers 21, these filter beds consisting of the usual bed of coke, gravel, filter-cloths, sponges or the like supported by any suitable 40 means such as the perforated plates 61 and one or more of these filter beds may be fitted as desired.

Access or inspection doors 62, are shown fitted to the end plate 7 and to the outer shell 1 and 45 may be fitted in any suitable position which will give convenient access to the interior of the apparatus, such as for changing the filter beds from time to time.

Figs. 7 and 8 show modified constructions of the 50 oil-discharge valve operating gear, in which the valve is arranged to be closed by spring action but opened by power operated means.

In Fig. 7 the cylinder 45 is attached to the body of the valve 6 by pillars 63 or the like, but the piston-rod 46 is extended downwards through a gland 64 in the lower end of the cylinder and to it is attached a cross member 65 which is capable of sliding on guides 66 rigidly attached to cylinder 45 and at their lower end to a member 67, suitably 60 designed to support a helical spring 68 which is secured between the members 65 and 67 and is designed to give a pressure load, which will thrust member 65 and piston-rod 46 upwards and so close valve 6, whenever the top side of the piston 69 is open to exhaust. The cylinder space below the piston has a port opening 70, which is always open to exhaust but never to pressure. The cylinder space above piston 69, has a port opening 71 which is alternatively open to pressure 70 or exhaust, according to the position of the slide-valve 72, which in this case, is attached directly to the rod 52 carrying the triggers 53 and 54 which are actuated by the movement of the external float-lever 42.

As shewn in Fig. 7, the valve 6 is shut, as the

spindle 52 has previously been moved by lever 42 to put valve 72 in a position which connects port 71 with the exhaust port so that the top of piston 69 is relieved of pressure thereby allowing spring 68 to close valve 6. As dome 3 fills, lever 42 will rise and in due course engage with trigger 54 and carry it to the position shown in dotted outline above it, and so pull the slide-valve 72 to the position in which exhaust connection is cut off from port 71 and fluid under pressure is admitted thereto instead. Piston 69 is therefore pushed downwards against the action of spring 68 and so opens valve 6 to allow oil to be discharged. As the dome 3 empties, lever 42 falls and moves valve 72 so that pressure is released from the top of piston 69 and spring 68 immediately closes valve 6. These operations continue as the dome 3 alternately fills and is emptied. This arrangement provides a definite means of ensuring that the valve 6 remains closed whenever power is definitely cut off from the cylinder 45 or when the separator is not in use.

Fig. 8 shows an arrangement somewhat similar to the arrangement of Fig. 7, but in which the cylinder 45 is placed alongside the valve 6 and small spiral springs 73, arranged round the guides 66 are used instead of the single spring as in Fig. 7. Whilst the cycles of operation for this mechanism are similar to that shown in Fig. 7, in this case the power from piston 69 for opening the valve 6 is transmitted by a lever or twin levers 74 pivoted at 75 in a bearing carried on a bracket or arm 76, the lever or levers 74 being connected to the piston rod 46 and member 65 by links 77, 78 respectively.

Figs. 9 to 12 illustrate a smaller construction of separator designed to deal with a main flow of a lighter fluid than the contaminating one to be separated, such as petrol and water, respectively, the separator according to the present 40 invention being so designed that it only requires to be inverted and used in the inverted position, to enable the heavier liquid to be separated and drained off, whilst allowing the main flow of lighter liquid to continue.

The construction of this latter type of separator, which is suitable for insertion in the feed-pipe to the carburettor of a petrol engine, is in general, the same as the construction described with reference to Fig. 1 and similar references have therefore been used for similar parts. In this construction, however, the shells 1 and 2, are cut longitudinally to form top and bottom halves and are secured together in their working condition by flanges 79 and bolts or screws 80. The oil flow directing flanges indicated by reference 24 in Figs. 1, 2, 4 and 5, are here shown in an alternative form, in which they are made as a tubular extension 24¹ of shell 2. In this construction also, particularly in the case of petrol separation, the deflector 10 is omitted, as the heavy impacting of petrol is not so important, as it coalesces freely, and, if desired, an additional port 13^b may be added in the division plate 12.

In this construction also the dome 3, or, in this case, a sump, consists of a glass cylinder 81 in order to permit of visible observation of the collection of water in the dome or sump 3.

The glass cylinder 81 is secured in place by a 70 cover 82, which is attached to shell 1 by screwed pillars 83 provided with wing-nuts 84 or the like, the cylinder 81 fitting into annular recesses 85 in the cover 82 and casing 1 and provided with packing or jointing rings 86. A drain cock 87

is fitted in the cover 82 for draining off accumulated water from the chamber. Instead of the hand operated cock 87, a float and needle valve, of the type used in petrol carburettors, 5 could be fitted for the purpose of automatically discharging the accumulated water, the float, of course, being arranged to sink in petrol and float in water, and so raise the needle valve and open the outlet when a predetermined quantity of 10 water has collected.

To reduce manufacturing costs as much as possible, the modified design for petrol separation could be made up from stampings or pressings, welded, brazed, or soldered together without 15 any flanges or other means for giving access to the interior, since, in the absence of internal mechanical parts, it may be unnecessary to give the user any such means of access.

In addition the use of glass for constructing 20 the cylinder 81 may be avoided and this cylinder 81 made of any suitable metal or other material as in the other constructions.

The construction shown in Figs. 9, 10, 11 and 25 12, is provided with suitable brackets or feet 88 for securing the apparatus in any required position, while, in the previously described constructions, suitable chairs or seatings 89 for supporting and securing the separator in its working 30 position are indicated in dotted lines, but alternative supports of any suitable design may be employed to suit the installation of the apparatus in each individual case as found necessary.

Figs. 1 to 6 shew a construction of separator 35 made from steel plates and standard angle bar sections and the like, welded or riveted together, but if desired the construction may be built up from castings of any suitable material, bolted, riveted or welded together, or by employing a combination of plates and such castings and the 40 like.

What I claim as my invention and desire to 45 secure by Letters Patent is:—

1. Apparatus for the separation of liquids of 50 different specific gravities comprising an outer shell of ovate form in vertical cross-section with its sides converging downwardly, a smaller inner shell also of ovate form in vertical cross-section 55 similarly arranged inside the outer shell at the top thereof and constituting a first-stage quiescence chamber, a collecting dome or chamber, for the liquid of lower specific gravity, secured to the top side of said outer shell and centrally thereof, an opening in said inner shell beneath the collecting dome by which the inner shell is in communication therewith, an inlet opening at one 60 end of said inner shell, a vertical baffle plate adjacent the inlet and dividing off part of the inner shell to form a swirl chamber, an opening in the bottom of the inner shell, at the opposite end to the inlet, by which the inner shell is in communication with the outer shell, division plates extending between the inner and outer shells and dividing the space therebetween into a number of lower quiescence chambers communicating with the collecting dome, an outlet opening at the bottom of 65 said outer shell, and means for drawing off the lighter separated liquid from the collecting dome.

2. Apparatus for the separation of liquids of 70 different specific gravities, according to claim 1, characterized in that a flare-mouthed direction plate is provided over the inlet opening to direct the flow downwardly on to a deflector so as to set up a swirling motion in the liquid.

3. Apparatus for the separation of liquids of

75 different specific gravities comprising an outer shell of ovate form in vertical cross-section with its sides converging downwardly, a smaller inner shell also of ovate form in vertical cross-section 80 similarly arranged inside the outer shell at the top thereof and constituting a first-stage quiescence chamber, a collecting dome or chamber, for the liquid of lower specific gravity, secured to the top side of said outer shell and centrally thereof, an opening in said inner shell beneath the collecting dome by which the inner shell is in communication therewith, an inlet opening at one 85 end of said inner shell, a vertical baffle plate adjacent the inlet and dividing off part of the inner shell to form a swirl chamber, an opening in the bottom of the inner shell, at the opposite end to the inlet, by which the inner shell is in communication with the outer shell, baffle plates on both sides of said opening to deflect the flow 90 in an upward direction before and after its passage through said opening, division plates extending between the inner and outer shells and dividing the space therebetween into a number of lower quiescence chambers communicating with the collecting dome, baffle plates in said chambers to deflect the flow upwardly, an outlet opening at the bottom of said outer shell, and means for drawing off the lighter separated liquid from the collecting dome.

4. Apparatus for the separation of liquids of 95 different specific gravities comprising an outer shell of ovate form in vertical cross-section with its sides converging downwardly, a smaller inner shell also of ovate form in vertical cross-section 100 similarly arranged inside the outer shell at the top thereof and constituting a first-stage quiescence chamber, a collecting dome or chamber, for the liquid of lower specific gravity, secured to the top side of said outer shell and centrally thereof, the top sides of said outer and inner shells being 105 made to slope upwardly towards said dome to assist the flow of lighter liquid into said dome, an opening in said inner shell beneath the collecting dome by which the inner shell is in communication therewith, an inlet opening at one 110 end of said inner shell, a vertical baffle plate adjacent the inlet and dividing off part of the inner shell to form a swirl chamber, an opening in the bottom of the inner shell, at the opposite end to the inlet, by which the inner shell is in communication with the outer shell, division plates extending between the inner and outer shells and dividing the space therebetween into a number of lower 115 quiescence chambers communicating with the collecting dome, an outlet opening at the bottom of said outer shell, and means for drawing off the lighter separated liquid from the collecting dome.

5. Apparatus for the separation of liquids of 120 different specific gravities comprising an outer shell of ovate form in vertical cross-section with its sides converging downwardly, a smaller inner shell also of ovate form in vertical cross-section 125 similarly arranged inside the outer shell at the top thereof and constituting a first-stage quiescence chamber, a collecting dome or chamber, for the liquid of lower specific gravity, secured to the top side of said outer shell and centrally thereof, an opening in said inner shell beneath the collecting dome by which the inner shell is in communication therewith, a baffle around said 130 opening to assist in directing the lighter liquid into the collecting dome and to prevent eddy currents from the main flow from disturbing the liquid in said dome, an inlet opening at one end of said inner shell, a vertical baffle plate adja- 135

cent the inlet and dividing off part of the inner shell to form a swirl chamber, an opening in the bottom of the inner shell, at the opposite end to the inlet, by which the inner shell is in communication with the outer shell, division plates extending between the inner and outer shells and dividing the space therebetween into a number of lower quiescence chambers communicating with the collecting dome, an outlet opening at the bottom of said outer shell, and means for drawing off the lighter separated liquid from the collecting dome.

6. Apparatus for the separation of liquids of different specific gravities comprising an outer shell of ovate form in vertical cross-section with its sides converging downwardly, a smaller inner shell also of ovate form in vertical cross-section similarly arranged inside the outer shell at the top thereof and constituting a first-stage quiescence chamber a collecting dome or chamber, for the liquid of lower specific gravity, secured to the top side of said outer shell and centrally thereof, the top sides of said outer and inner shells being made to slope upwardly towards said dome to assist the flow of lighter liquid into said dome, an opening in said inner shell beneath the collecting dome by which the inner shell is in communication therewith, a baffle around said opening to assist in directing the lighter liquid into the collecting dome and to prevent eddy currents from the main flow from disturbing the liquid in said dome, an inlet opening at one end of said inner shell, a vertical baffle plate adjacent the inlet and dividing off part of the inner shell to form a swirl chamber, an opening in the bottom of the inner shell, at the opposite end to the inlet, by which the inner shell is in communication with the outer shell, baffle plates on both sides of said opening to deflect the flow in an upward direction before and after its passage through said opening, division plates extending between the inner and outer shells and dividing the space therebetween into a number of lower quiescence chambers communicating with the collecting dome, baffle plates in said chambers to deflect the flow upwardly, an outlet opening at the bottom of said outer shell, and means for drawing off the lighter separated liquid from the collecting dome.

7. Apparatus for the separation of liquids of different specific gravities comprising an outer shell of ovate form in vertical cross-section with its sides converging downwardly, a smaller inner shell also of ovate form in vertical cross-section similarly arranged inside the outer shell at the top thereof and constituting a first-stage quiescence chamber, a collecting dome or chamber, for the liquid of lower specific gravity, secured to the top side of said outer shell and centrally thereof, an opening in said inner shell beneath the collecting dome by which the inner shell is in communication therewith, an inlet opening at one end of said inner shell, a vertical baffle plate adjacent the inlet and dividing off part of the inner shell to form a swirl chamber, an opening in the bottom of the inner shell, at the opposite end to the inlet, by which the inner shell is in communication with the outer shell, division plates extending between the inner and outer shells and dividing the space therebetween into a number of lower quiescence chambers communicating with the collecting dome, an outlet opening at the bottom of said outer shell, and means for drawing off the lighter separated liquid from the collecting dome, comprising a draw-off valve operated by power mechanism under the

control of a float arranged within the collecting dome and connected by levers with a shaft which projects through the side of said dome and carries an external lever which controls the mechanism operating the valve.

8. Apparatus for the separation of liquids of different specific gravities comprising an outer shell of ovate form in vertical cross-section with its sides converging downwardly, a smaller inner shell also of ovate form in vertical cross-section similarly arranged inside the outer shell at the top thereof and constituting a first-stage quiescence chamber, a collecting dome or chamber, for the liquid of lower specific gravity, secured to the top side of said outer shell and centrally thereof, an opening in said inner shell beneath the collecting dome by which the inner shell is in communication therewith, an inlet opening at one end of said inner shell, a vertical baffle plate adjacent the inlet and dividing off part of the inner shell to form a swirl chamber, an opening in the bottom of the inner shell, at the opposite end to the inlet, by which the inner shell is in communication with the outer shell, division plates extending between the inner and outer shells and dividing the space therebetween into a number of lower quiescence chambers communicating with the collecting dome, an outlet opening at the bottom of said outer shell, a float within said collecting dome, levers connected to said float and secured to a shaft projecting through the side of said dome, an external control lever on the outer end of said shaft, a draw-off valve by which the liquid collected in said dome is drawn off, said valve being operated by a piston, coupled by its piston rod to the spindle of said valve, working within a cylinder under the control of a piston-valve, an operating rod connected to said piston-valve, and triggers on said rod engaged by said control lever whereby the piston-valve is moved to cause the main piston to open or close said draw-off valve according to the position of the float within said dome.

9. Apparatus for the separation of liquids of different specific gravities according to claim 8, wherein the draw-off valve is maintained in or returned to, its closed position by a spring, the power mechanism opening said valve against the action of said springs.

10. Apparatus for the separation of liquids of different specific gravities comprising an outer shell of ovate form in vertical cross-section with its sides converging upwardly, a smaller inner shell also of ovate form in vertical cross-section similarly arranged inside the outer shell at the bottom thereof and constituting a first-stage quiescence chamber, a collecting dome or sump, for the liquid of higher specific gravity, secured to the bottom of said outer shell and centrally thereof and communicating therewith, an opening in said inner shell above the collecting dome by which the inner shell is in communication therewith, an inlet opening at one end of said inner shell, an opening in the top of the inner shell, at the opposite end to the inlet, by which the inner shell is in communication with the outer shell, division plates extending between the inner and outer shells and dividing the space therebetween into a number of quiescence chambers communicating with the sump, an outlet opening at the top of said outer shell, and means for running off the heavier separated liquid from the sump.

11. Apparatus for the separation of liquids of

different specific gravity comprising an outer shell of ovate form in vertical cross section with its sides converging upwardly, a smaller inner shell also of ovate form in vertical cross section 5 with its sides converging upwardly, formed at the bottom of said outer shell and constituting a first stage quiescence chamber, an inlet opening at one end of said inner shell, an opening in the top of said inner shell at the opposite 10 end to the inlet, by which the inner shell is in communication with the outer shell, a curved baffle plate over said opening in the top of the inner shell, division plates attached to said inner and outer shells and extending into the space 15 therebetween and dividing it into a number of additional quiescence chambers, an outlet opening at the top of said outer shell, an opening at the bottom of said inner shell, a flange surrounding said opening, an opening in said outer 20 shell below said opening in the inner shell, a cylindrical fitting extending below the opening in the outer shell and constituting a sump for the collection of the heavier separated liquid, a cover plate over the lower end of said fitting, 25 screwed pillars extending from said outer shell through said cover plate, wing nuts on said pillars retaining said cover in position and a drain cock in said cover plate for draining off the heavier liquid collected in said sump.

30 12. Apparatus for the separation of liquids of different specific gravity comprising an outer shell of ovate form in vertical cross section with its sides converging upwardly, a smaller inner shell also of ovate form in vertical cross section 35 with its sides converging upwardly, formed at the bottom of said outer shell and constituting a first stage quiescence chamber, said outer and inner shells being formed in two parts connected together by flanges formed thereon and bolted 40 together, an inlet opening at one end of said inner shell, a baffle placed adjacent said inlet, an opening in the top of said inner shell at the opposite end to the inlet, by which the inner shell is in communication with the outer shell, flanges on 45 either side of said opening, a curved baffle plate over said opening in the top of the inner shell, division plates attached to the outer face of said inner shell and alternating with division plates attached to the inner face of said outer shell, 50 said division plates extending into the space between the outer and inner shells and dividing it into a number of additional quiescence chambers, an outlet opening at the top of said outer shell, an opening at the bottom of said inner shell, a flange surrounding said opening, an opening in 55 said outer shell below said opening in the inner shell, a recess surrounding said opening in said outer shell, a cylindrical fitting extending below the opening in the outer shell and fitting into said recess and constituting a sump for the collection of the heavier separated liquid, a cover plate over the lower end of said fitting, a recess in said cover plate into which the lower end of said cylindrical fitting projects, packing washers in said recesses, 60 screwed pillars extending from said outer shell through said cover plate, wing nuts on said pillars retaining said cover in position and a drain cock in said cover plate for draining off the heavier liquid collected in said sump.

65 13. Apparatus for the separation of liquids of

different specific gravities comprising a housing ovate in transverse section, a partition extending longitudinally of the housing below the greatest horizontal cross-sectional area whereby to divide the housing into an upper intake portion and a lower outlet portion, a plurality of quiescence chambers in the upper portion through each of which the mixture of liquids to be separated is passed in turn, a collecting chamber arranged above the quiescence chambers and communicating therewith, an inlet for said mixture in each quiescence chamber, and an outlet in the lower portion of the housing, said partition having an opening therethrough to permit the passage of liquid from the upper portion of the housing to 15 the lower portion of the housing, said outlet being arranged forwardly of said opening.

14. Apparatus for the separation of liquids of different specific gravities comprising a housing ovate in transverse section with the narrowest 20 portion lowermost, a partition extending across the housing below the widest portion thereof and extending longitudinally of the housing to divide the housing into an upper portion and a lower portion, a collecting chamber communicating with the upper portion, means for dividing the upper portion into a plurality of communicating quiescence chambers, an inlet for discharging the mixture of liquids into the upper portion adjacent one end of the housing, said partition having an 25 opening therethrough adjacent the opposite end of the housing, said housing having an outlet in the lower portion adjacent the end opposite from said opening in said partition.

15. Apparatus for the separation of liquids of 30 different specific gravities comprising an elongated housing ovate in transverse section with the narrowest portion lowermost, a partition extending across the housing and longitudinally thereof to divide the housing into an upper portion and a lower portion, a collecting chamber communicating with the upper portion, means for dividing the upper portion into a plurality of communicating end abutting quiescence chambers, an inlet for discharging the mixture of liquids into the upper portion adjacent one end of 35 the housing, said partition having an opening therethrough adjacent the opposite end of the housing, said housing having an outlet in the lower portion adjacent the end opposite from said opening in said partition.

16. Apparatus for the separation of liquids of different specific gravities, comprising a plurality of quiescence chambers of ovate shape in vertical cross section, through each of which the mixture of liquids to be separated is passed in turn, an inlet for said mixture and outlets for each of the separated liquids, a collecting dome or chamber, arranged out of the direct line of flow of the mixture in which one of the separated liquids is collected, and means for drawing off the separated liquid from said dome, said quiescence chambers being formed by two shells of ovate form in vertical cross-section arranged one inside the other with division plates extending between them so that the space between the outer and inner shells constitutes a number of quiescence chambers having passages converging in the direction of flow towards the collecting dome.

HERBERT ALEXANDER THOMPSON. 70
